UNITED STATES PATENT OFFICE

140,107

DESIGN FOR A LUMINAIRE FOR FLUORESCENT AND INCANDESCENT LAMPS

Joshua Gordon Lippincott, Scarsdale, N. Y., assignor to Holophane Company, Inc., New York, N. Y., a corporation of Delaware

Application August 12, 1944, Serial No. 114,853

Term of patent 7 years

(Cl. D48—23)

To all whom it may concern:

Be it known that I, Joshua Gordon Lippincott, a citizen of the United States of America and a resident of Scarsdale, in the county of Westchester and State of New York, have invented a new, original, and ornamental Design for a Luminaire for Fluorescent and Incandescent Lamps, of which the following is a specification, reference being had to the accompanying drawing, forming a part thereof.

In this drawing:

Figure 1 is a perspective view of a luminaire for fluorescent and incandescent lamps from underneath showing my new design;

Figure 2 is a side elevational view of the same on a reduced scale;

Figure 3 is an inverted plan view of the same on the same scale as Figure 2; and

Figure 4 is a fragmentary view of the same at an enlarged scale.

The luminaire is characterized by having a light diffusing bottom portion below the line A—A of Figure 2 interrupted by round lenses indicated by the circles in Figures 1, 3 and 4.

I claim:

The ornamental design for a luminaire for fluorescent and incandescent lamps, as shown and described.

JOSHUA GORDON LIPPINCOTT.
